US00D600627S

(12) **United States Design Patent**
Toll et al.

(10) **Patent No.:** **US D600,627 S**
(45) **Date of Patent:** **** Sep. 22, 2009**

(54) **WATER BOTTLE SUPPORT ARM**

(75) Inventors: **Steven G. Toll**, Tampa, FL (US); **John Cobb**, Tyler, TX (US)

(73) Assignee: **Tampa Bay Recreation, LLC.**, Tampa, FL (US)

(**) Term: **14 Years**

(21) Appl. No.: **29/324,863**

(22) Filed: **Sep. 22, 2008**

(51) **LOC (9) Cl.** **12-11**

(52) **U.S. Cl.** **D12/411**

(58) **Field of Classification Search** **D12/411, D12/114, 223, 111, 419, 420, 162, 407; D8/349, D8/354; 280/288.4, 477, 495; D7/620; 248/310, 248/311.2, 312, 313, 314, 312.1, 316.1, 248, 248/200, 205.1, 187, 300; 224/42.11, 412-414, 224/419-427, 430, 431, 433, 440, 441, 443, 224/447, 450, 451, 454, 459, 461, 462, 275, 224/528-533**

(57) **CLAIM**

The ornamental design for a water bottle support arm, as shown and described.

DESCRIPTION

FIG. 1 is a perspective view of our ornamental design;

FIG. 2 is a right side elevation view of the ornamental design of FIG. 1;

FIG. 3 is a left side elevation view of the ornamental design of FIG. 1;

FIG. 4 is top plan view of the ornamental design of FIG. 1;

FIG. 5 is bottom plan view of the ornamental design of FIG. 1;

FIG. 6 is front elevation view of the ornamental design of FIG. 1;

FIG. 7 is rear elevation view of the ornamental design of FIG. 1; and,

FIG. 8 is a perspective view of the ornamental design of FIG. 1 with broken lines showing environment, which is shown for illustrative purposes only and forms no part of the claimed design.
